his Atty.

UNITED STATES PATENT OFFICE.

LAWRENCE C. NELSON, OF CHICAGO, ILLINOIS, ASSIGNOR TO STEWART MANUFACTURING CORPORATION, OF CHICAGO, ILLINOIS, A CORPORATION OF DELAWARE.

CARRIAGE-CURTAIN WINDOW FRAME.

Application filed May 8, 1922. Serial No. 559,148.

To all whom it may concern:
Be it known that I, LAWRENCE C. NELSON, a citizen of the United States, residing in the city of Chicago, in the county of Cook 5 and State of Illinois, have invented certain new and useful Improvements in Carriage-Curtain Window Frames, of which the following is a specification, reference being had to the accompanying drawings, forming a 10 part thereof.

The purpose of this invention is to provide an improved construction of a carriage curtain window frame, particularly adapted for affording secure engagement of the curtain fabric between the frame members. It 15 consists in the elements and features of construction shown and described, as indicated in the claims.

In the drawings:—
20 Figure 1 is an elevation view of a carriage curtain window with the carriage curtain fabric partly broken away and one member of the window frame partly broken out to disclose interior details.

25 Figure 2 is a section on a magnified scale at the line, 2—2, on Figure 1.

Figure 3 is a section on a magnified scale 30 at the line, 3—3, on Figure 1.

Figure 4 is a magnified view of a section 35 at the curved line, 4—4, on Figure 1, developed into a plane.

Figure 5 is a plan view of a fabric-engaging clip in a modified form resulting 40 from combining in one piece a corner clip and a side clip.

In the structure shown in the drawings 45 the carriage curtain is shown double, consisting of inner and outer fabrics, A, A, which enfold the inner and outer frame members, B, B, respectively, the said fabric sheets having apertures for the windows cut in them considerably smaller than the openings in the frames, so that the marginal portions around the apertures of the fabrics 50 are folded through the frame openings and back outwardly between the frame members, as clearly seen in Figures 2 and 3. The frame members, B, B, are rabbeted at their inner margins, as seen at b, b, to accommodate rubber gaskets, D, D, and the 55 margin of the glass, F. The rubber gaskets are desirably originally in the form of rubber tubing as indicated in dotted line in Fig. 2, having a limited bore or axial cavity

for increasing their yieldingness under the 55 compression to which they are subjected in clamping the frame members together upon the glass; so that these gaskets are distorted as seen in the cross-sectional views, Figures 2 and 3, in the compression of the fabric 60 and the frame together, and are spread out into the otherwise unoccupied space of the rabbet, appearing in different form at different parts, according to the space which varies somewhat by reason of being provided for the fabric-engaging clips, as hereinafter described.

The characteristic of the present invention consists in these clips for engaging the fabric and the manner of placing the same 70 for that purpose, as will now be described. The corners of the frame being rounded as shown in the drawings, the margin of the fabric which is folded back as described, between the frame members for engagement 75 is slotted radially with respect to the curve of the rounded corner, the slits reducing the fabric at this point to radially projecting fingers, a, a, as seen in Figure 1. In the outer marginal area of the abutting faces 80 of the frame members, B, B, beyond the rabbets, there are formed at the rounded corners seats for arcuate clip members, G, which have struck out from them clip fingers, g, with which the radial fabric fingers, a, are engaged; so that when the two frame members are clamped together, the fabric fingers are clinched in the apertures from 85 which the clip fingers are struck, seen in section in Figure 2. At other points along the 90 straight sides and ends of the frame there are formed in the marginal areas of the abutting faces outside the rabbet, seats for small clips, H, which are angle-shaped in 95 their original formation having the finger, h, projecting at right angles to the plane of said abutting faces in which the clips are seated, and the fabric is slotted for insertion of these clip fingers through the slits, the fingers being then clinched down 100 upon the fabric as seen in Figure 3. The slitting of the fabric to cause these fingers may then be done by the clip fingers themselves, the fabric being drawn around the frame to proper position and pressed down 105 upon the up-standing clip fingers.

The frame members, B, B, are designed to be made by die casting, and in the process

of casting there are formed in the seats for the clips, G and H, respectively, and projections, b^2 , for engaging apertures, g^2 and h^2 , in the clips respectively, the projections, 5 b^2 , being then headed down and riveted for holding the clips in their seats.

As seen in Figure 5 the arcuate corner clips, G, may be made in one piece with a clip, H, at each end—of the arc—thus reducing by eight the number of pieces to be 10 handled in each assemblage.

I claim:—

1. A carriage curtain window frame comprising in combination with two frame members between which a glass may be clamped, curtain-engaging clips securely lodged in one frame member in the face thereof at which said frame member is seated against the other member for engaging the curtain 20 there-between, said clips being adapted for engaging the surface of the curtain fabric at a marginal area thereof adjacent to an edge of the fabric past which said clips project, one of the two engaged elements, 25 viz., the clip and the fabric, being folded about an edge of the other for securing the engagement.

2. A carriage curtain window frame comprising in combination with two frame members between which the fabric of the carriage curtain and the glass may be clamped, the curtain having the margin about the window opening folded in through said opening of the frame, and back for 35 wrapping the frame, one or both of the frame members being rabbeted for accom-

modating the thickness of the glass, the en- 40 wrapping fabric marginal area extending over the rabbet area and onto the marginal area of the frame member outside the rabbet, and clips securely lodged in the last mentioned area adapted for engaging slit-edges of the fabric, the fabric being slitted to form edges for such engagement.

3. In the construction defined in claim 2, 45 foregoing, the frame having rounded corners and the fabric being slitted radially with respect to the curve of said corners to form fingers for engaging the clips, the clips at such rounded corners consisting each of 50 an arcuate strip having fingers struck out of its plane for engaging the fabric fingers under the slip fingers; whereby such fabric fingers are clamped into the apertures from which the clip fingers are struck in clamp- 55 ing the two frames together onto the glass and fabric.

4. In the construction defined in claim 2, 60 foregoing, an arcuate clip for engaging an arcuate portion of the contour, having fab- 65 ric-engaging fingers struck out from its plane for being clinched onto fabric tongues which may be inserted under said fingers, and having at the ends of the arc lugs up- turned from said plane for penetrating the fabric adapted to be clinched down thereunto.

In testimony whereof, I have hereunto set my hand at Chicago, Illinois, this 4th day of May, 1922.

LAWRENCE C. NELSON.
